UNITED STATES PATENT OFFICE

WALES ALDRICH, OF DAYTON, OHIO.

CASH REGISTER AND INDICATOR.

SPECIFICATION forming part of Letters Patent No. 380,542, dated April 3, 1888.

Application filed February 14, 1887. Serial No. 227,466. (No model.)

To all whom it may concern:

Be it known that I, WALES ALDRICH, of Dayton, in the county of Montgomery and State of Ohio, have invented certain new and useful Improvements in Cash Registers and Indicators; and I do hereby declare the following to be a full, clear, and exact description of the same, reference being had to the accompanying drawings, forming part of this specification, and to the figures and letters of reference marked thereon.

My present invention relates to that class of machines which perform the functions of serving as a check upon dishonest employés who handle the cash in a business establishment and as a means for keeping an accurate account of the cash receipts during any given period.

The machine which I have designed for carrying out my invention embodies a series of keys each representing a particular amount, a series of targets or visual signals corresponding to the series of keys and adapted to be exposed when said keys are operated, an alarm mechanism, a registering mechanism, and a mechanism by means of which the cash-drawer is released, the whole being so arranged as that when a cash purchase is made and the key or keys corresponding to the amount of the purchase is or are operated a target or targets indicating the amount will be exposed to the view of both employé and purchaser, the alarm will be sounded, a record made of the transaction upon the registering mechanism, and the money-drawer released or unlocked, so that the amount received from the purchaser may be deposited therein and change made, if necessary.

I will first describe my machine at length, and will then point out what I deem its particular features of novelty in the clauses of claim at the end of this specification.

Referring to the accompanying drawings, Figure 1 represents a perspective view of a machine constructed in accordance with my invention; Fig. 2, a side view of the same with the casing removed; Fig. 3, a perspective view of a portion of the mechanism, showing one key-bar, its corresponding target, and the intermediate mechanism for operating it, the alarm mechanism, and portion of the registering mechanism. Fig. 4 is a horizontal section

taken on the line α α of Fig. 2, showing in dotted lines the position the parts occupy when the key-bar is pulled out, the tablet exposed, and the registering device operated. Fig. 5 is a top plan view of the mechanism shown in Fig. 2. Fig. 6 is a detail view showing in elevation the registering mechanism. Fig. 7 is a view of the gear and the actuating spring for returning or resetting the registering mechanism; Fig. 8, a detail view of the bell and the trip mechanism applied to the hammer thereof. Fig. 9 is a longitudinal vertical section taken through the casing of the machine, and showing particularly the means for locking and releasing the money-drawer.

Similar letters of reference in the several figures indicate the same parts.

The letter A indicates a suitable casing constructed of wood or other material, and of a form which, aside from its adaptability to the inclosed mechanism, may be varied to suit the taste of the designer.

Glazed openings B are provided at the upper portion of the casing for the exhibition of the targets or visual signals employed in the machine, other glazed openings, C C, being provided at the sides to enable the body of the mechanism to be inspected, as well as an opening, D, closed by a hinged cover, E, for enabling the register to be exposed to view and be reset when necessary. This cover E is preferably kept locked, so as to be accessible to no one but the person holding the key. At the bottom of the casing is arranged a drawer, F, which, when in place, is adapted to be held closed by a top, G, that is itself locked and unlocked by means of devices to be hereinafter described.

Within the casing is arranged a metal frame, H, that is adapted to receive and maintain in their proper relations all of the operative parts of the machine, except some of the devices shown in Fig. 9, employed for locking and unlocking the money-drawer. For convenience of description this frame H and the mechanism borne by it are shown removed from the casing in most of the figures.

Referring particularly to Figs. 2, 3, and 4, K will be found to represent a series of horizontal bars arranged one above the other and supported at front and rear upon stationary arms or fingers I I', formed upon the metal

frame. These bars I term, for convenience, "key-bars." Each of them near its outer end is pivoted to a hinged link, L, which serves to guide and steady it in its reciprocating movements and allow the lateral movement necessary to cause the key-bar to properly operate upon the vibratory bar and the shaft to which the registering mechanism is geared, and at its extreme outer end, outside of the casing, it is provided with a loop or eye, K', to enable the operator to conveniently operate it with his finger. On this eye or loop K' is formed or affixed the figure or number which the particular bar is intended to designate in practically using the machine.

M M, &c., Figs. 2 and 3, represent a series of bell-crank levers, as many in number as there are key-bars. Each of these bell-crank levers is mounted so as to turn freely upon a vertical rod or pivot, N, and one of the arms, m, projects in the path of a lug or projection, K², on its corresponding key-bar K, while its other arm, m', bears a vertical rod or staff, O, which carries at its upper end a target or tablet, O', upon which is marked on both sides a figure or number corresponding to that on the end of the key-bar. All the targets normally stand swung around to one side out of line with the opening B in the casing; but when any one of the key-bars is pulled the projection K² upon it strikes the arm m of the co-operating bell-crank lever and turns said lever on its pivot, thereby bringing the target carried by said lever to the opening B, where it will be visible to both the operator and the purchaser whether they both be at the front or one at the front and the other behind the machine.

P represents a bar mounted so as to turn freely upon a vertical rod or pivot, P', and having a series of rigid lateral arms or fingers, p, that project beneath the series of key-bars and are adapted to be operated upon by lugs or projections K³, formed on said key-bars, as shown in Figs. 2 and 3. These arms p are arranged spirally upon the bar P, the effect of which is to cause the topmost arm of the series to stand normally at the greatest distance from its co-operating lug K³ on the corresponding key-bar and the lowest of said series of arms to stand nearest to its co-operating lug, so that while a considerable extent of movement of the uppermost key-bar will be required in order to bring its lug K³ into engagement with the arm p, only a comparatively short movement of the lowest key-bar will be necessary to render it operative upon the arm p. The links L and bar T causing the projections on the key-bars to move in the arc of a circle of which the center of bar P is the center render it necessary to arrange the arms p in a spiral line.

Whenever either of the key-bars is pulled or withdrawn to its full extent, its lug K³ strikes the arm p in its path and turns the bar P on its axis a greater or less distance, accordingly as said engagement between the lug and arm occurred sooner or later, thereby

causing an arm, Q, secured to the upper end of the bar P and bearing a spring-pressed pawl, Q', which is in engagement with a ratchet-wheel, R, to rotate said ratchet-wheel and through it set in motion the driving-gear S of a registering mechanism, the construction of which will be farther on explained. To an arm, P⁴, on the lower end of the bar P is connected (by a link, P⁵) a spring, P⁶, Figs. 3 and 4, which is put under compression each time the bar P is turned and tends to bring said bar back to normal position.

T represents a bar mounted on a vertical axis, T', at the rear of the frame H and having a series of arms, t, with which the T-shaped ends of the key-bars are adapted to engage. This bar T has an arm, t², Fig. 4, to which a spring, t³, is connected by means of a link, t⁴. Upon the pulling of any one of the key-bars this bar T is vibrated on its pivot against the tension of said spring t³. The position the parts occupy when the key-bar is pulled is shown in dotted lines, Fig. 4.

The uppermost arm of the bar T is provided with a cam projection, t⁵, which, when the bar is vibrated, is adapted to engage with a depending arm, U, secured to a rock shaft, U', as shown clearly in Fig. 3. This rock-shaft U' bears at its opposite end a tripping arm or lever, U², that is adapted to engage with a pivoted latch, U³, which operates upon the arm U⁴ on the hammer U⁴ of a bell, U⁵. Every time the bar T is turned in response to a pull upon one of the key-bars the shaft U' is rocked and the bell is rung. Also mounted on the rock-shaft U' is an arm, V, Figs. 3, 2, 5, which bears at its extremity a friction-roller, v, and normally stands just above the upper end of a lever, V', pivoted to the side of the casing, as shown in Fig. 9. The lower end of this lever extends beneath an adjustable stop, V², located on a vertically-sliding bar or bolt, V³, whose lower end is adapted to engage with a notch, V⁴, formed in the top G of the money-drawer, as shown. Through a cross-piece, G', secured to this top G, passes a rod, G², which is secured to the back of the casing, and arranged upon this rod between the casing and the said cross-piece G' is a spiral spring, G³.

When the rock-shaft U' is turned in consequence of a pull being made upon one of the key-bars, the bar V³ will, through the described connections, be raised out of engagement with the notch V⁴, and the spring G³, asserting itself, will force the top G of the money-drawer forward, and by thus releasing the drawer from the restraining effect of the shoulder V⁴ of said top enable the drawer to be pulled out.

From what has been stated it will be apparent that starting with the machine in normal position and with none of the targets or tablets exposed at the openings in the upper part of the casing, a pull upon any one of the key-bars will cause, first, a corresponding target or tablet to be exposed; secondly, a turning of the bar P and a registration upon the register-

ing mechanism; thirdly, the ringing of the bell, and, fourthly, the unlocking of the money-drawer. Upon the release of the key-bar so pulled and the pushing in of the money-drawer 5 and its top all the parts will resume their first position, excepting the registering mechanism, which retains a record of the transaction, and the target or tablet, which remains exposed at the openings. When another key-bar is pulled, 10 the operations are all repeated, save that the target or tablet is withdrawn from view and another one corresponding to the key-bar pulled is exhibited in its stead, and that the registering mechanism is given a greater or 15 less extent of movement, according to the amount designated.

The withdrawal of the target or tablet from the opening is effected by the mechanism and in the manner which I will now describe: Pivot 20 at W to the top of the metal frame, Figs. 2, 5, is a lever, W', to the rear end of which is hinged a gravitating piece or latch, W², the forward end of which lies in the path of a stop or projection, W³, on a plate, W⁴, that is 25 adapted to be reciprocated transversely of the frame and to carry with it a vertical rod, Z, which extends down between the arms of the bell-crank levers M, as shown in Fig. 4, and is stepped in a swinging arm, Z', hinged to the 30 rod or pivot N, as shown in Figs. 2, 3, 4. The piece or latch W² stands in the path of the cam projection t⁵ on the arm of the vibratory bar T, and when said bar T is vibrated in response to a pull upon a key-bar the said cam 35 projection, striking the said piece or latch W², causes the lever W' to be turned on the pivot W and its inner end to strike the projection W³ on the plate W⁴, and through said plate cause the rod Z to swing around, and, engaging 40 with the inner arm of the bell-crank lever carrying the target or tablet exposed at the opening, move said bell-crank lever back to normal position and in line with its fellows, and thus carry the said target or tablet away 45 from the opening out of view. This operation of withdrawing the exposed target or tablet from view is the first to be performed when a key-bar is pulled and does not interfere at all with the orderly and timely exposure of the 50 next target or tablet which is to indicate the manipulation of said key-bar.

The lever W' is reset automatically upon the return of the cam projection t⁵ to normal position, and the sliding plate W⁴ and tablet- 55 reTRACTING rod Z are brought back to normal position by the swinging around of the bell-crank lever, which brings the next target or tablet to view.

I will here state that to prevent any possible 60 interference of the targets or tablets with each other I have constructed the arms of the successive bell-crank levers which bear the target-shafts of different lengths, as shown in Fig. 2, and have arranged guides o for directing the staffs in their movements for separating them, and, by affording them lateral support, preventing them from becoming bent and

interlocked. These guides o are preferably composed of strips secured at one end to the frame, and are bent in the arc in which the staffs 70 of the tablets move, one strip being situated between each pair of staffs.

The registering mechanism is constructed as follows: With the gear-wheel S, hereinbefore referred to, there is meshed a small gear, 75 S', mounted on a long pinion-shaft, S². This pinion-shaft is adapted to be meshed with a gear, S³, on a shaft, S⁴, which shaft has also a pinion, S⁵, which engages a gear, S⁶, on a shaft, S⁷, that is in turn provided with a pinion, S⁸, 80 that meshes with a gear, S⁹, mounted on a shaft, S¹⁰, and connected through a volute spring, S¹¹, to a stationary drum, S¹², as shown in Figs. 6 and 7. The pinion-shaft S² has its bearing in the metal frame H, as shown in Fig. 6; but the 85 shafts S⁷ and S¹⁰ have their bearings in and are supported by a supplemental frame, S¹³, which is supported in a plate, S¹⁴, mounted on the frame H above the gears S S', as shown in Figs. 5 and 6. The pinion-shaft S² projects up 90 through suitable openings in the plate S¹⁴ and the frame S¹³, and is kept normally in engagement with the gear-wheel S³ by the action of a spring, S¹⁵, interposed between the flange of the plate S¹⁴ and the end of the frame S¹³. On 95 the upper end of the pinion-shaft S² is secured an indicator, S¹⁶, which co-operates with a dial laid off in divisions numbered from 0 to 9, inclusive, and is adapted to keep a register of transactions varying in amounts from one to 100 nine cents, while upon the upper ends of the shafts S⁴ S⁷ S¹⁰, respectively, there are secured other indicators, (lettered S¹⁷ S¹⁸ S¹⁹,) respectively, that are adapted to co-operate with other dials designed to register transactions varying 105 in amount from ten to ninety cents, from one to nine dollars, and from ten to ninety dollars, respectively.

Now, the key-bars are ten in number and are designated on their ends with figures from one to ten, inclusive, the uppermost bar being numbered 1, and so on in order to the lowest one, which is numbered 10. Whenever one of the key-bars is pulled out—the fifth bar, for instance, for a five-cent transaction—the fifth bar p of the series of arms projecting from the bar P will be engaged by the lug K³ on said fifth key-bar and will cause the vibration of said bar P a distance sufficient to cause the pawl P' to advance the ratchet-wheel R, and through the intermediate gearing turn the pinion-shaft S² until the indicator on its upper end uncovers the figure 5 of the dial beneath it. If the next transaction be a ten-cent transaction, key-bar No. 10 will be pulled and the registering train will be operated so as to cause the index S¹⁷ to move around and stand between the figures 10 and 20 on the second dial and the figure 5 on the first dial, the indicator on this last-named dial, which before stood at 5, having been by the recordation of the ten-cent transaction caused to make a complete revolution and brought back to starting-point. If the next transaction should be a dollar trans- 120 125 130

action, the key-bar 10 will have to be pulled ten times, and if a ten-dollar transaction a hundred times, the registry of these items being effected on the third and fourth dials, as will be readily understood.

Normally the spring S^{11} , Fig. 7, is kept partially wound up, and the gear S^9 , to which said spring is connected, is kept from backward movement by the engagement of a stop, S^{20} , located on the under side of the said gear, with a spring-detent, S^{21} , secured to the frame S^{13} , as shown in Fig. 6. The principal function of this spring S^{11} is to operate upon the train of gearing and run the register back to zero when it is so desired. To make this plainer, it should be borne in mind that each time the gear S^9 is turned as a consequence of the manipulation of the key-bars the spring S^{11} is wound up more and more, and when, at the end of the day's business, for instance, it is desired to reset the register to zero the frame S^{13} is given a slight longitudinal movement in the direction indicated by the arrow, Figs. 5 and 6, sufficient to compress the spring S^{15} and disengage the pinion S^3 from the pinion-shaft S^2 , whereupon the spring S^{11} , asserting itself, will cause the gear S^9 to rotate backward till its stop S^{20} comes again into contact with the spring-detent S^{21} , or, in other words, till all the indicators operated by the connected train are brought back to zero. The shifting of the frame S^{13} to effect this resetting operation can be accomplished either by moving said frame positively by hand or by turning a cam-lever, S^{22} , Fig. 5, till the pressure of its cam-surface against the adjacent wall of the casing effects the desired movement.

It should be stated that the openings in the frame S^{13} , through which the pinion-shaft S^2 passes, are made large enough to permit of the shifting of the said frame as above described.

Should the machine be so frequently used before resetting as to cause the gear S^9 to make a full revolution or more than a full revolution, the stop S^{20} will depress the spring-detent S^{21} and pass by the same, thus allowing the gear to move on uninterruptedly, and when subsequently it is desired to reset the register back to its normal state, it is only necessary, in addition to moving the frame S^{13} so as to throw the gear S^9 out of mesh with the pinion shaft S^2 , that the spring-detent S^{21} be depressed, so as to let the stop S^{20} pass by on its first backward revolution and then arrest it on its next revolution. A pin, S^{23} , projecting above the frame S^{13} and connected to the spring-detent, may be employed as a means of operating said detent.

Owing to the necessity of pulling more than one bar or of pulling the same bar a number of times to register a transaction involving an amount greater than ten cents, I preferably employ in practice three mechanisms substantially like the one herein shown and described—that is to say, one for use in dealing with amounts from one to nine cents, inclusive, an-

other with amounts of from ten cents to ninety-nine cents, inclusive, and still another with amounts including a dollar and multiples thereof, after the manner of the invention described in my patent, No. 342,059, dated May 18, 1886. These several mechanisms I preferably arrange alongside each other within a common casing, so that a single rock-shaft, U' , may be employed for ringing the bell and releasing the money-drawer top. Where such duplication of the mechanism is made, I preferably employ a separate register for each mechanism.

Having thus described my invention, what I claim as new is—

1. In a cash register and indicator, the combination, with a swinging arm bearing a target or tablet at a point removed from its pivot, of a reciprocating key-bar having a stop normally out of engagement with said arm, but adapted, when the key-bar is pulled, to positively engage it and move the target or tablet into view, substantially as described.

2. In a cash register and indicator, the combination, with a bell-crank lever having a target or tablet on one arm, of a reciprocating key-bar having a stop normally out of engagement with said lever, but adapted, when the key-bar is pulled, to positively engage the other arm of said lever and move the tablet into view, substantially as described.

3. In a cash register and indicator, the combination, with a series of swinging arms each bearing a target or tablet at a point removed from its pivot, of a series of reciprocating key-bars each bearing a stop normally out of engagement with its arm, whereby when any key-bar is pulled its stop will engage its corresponding arm, the latter will be turned, and the target or tablet borne by said lever brought to view, substantially as described.

4. In a cash register and indicator, the combination, with a series of bell-crank levers each of which bears upon one of its arms a target or tablet, of a series of corresponding key-bars each of which has a stop for co-operating with the other arm of its corresponding bell-crank lever, said stops being normally out of engagement with their levers, but arranged to positively engage and operate them when the key-bars are pulled, substantially as described.

5. In a cash register and indicator, the series of bell-crank levers mounted upon a common axis and having arms of different lengths, in combination with the targets or tablets supported by said arms and with the series of reciprocating key-bars having stops arranged to operate upon the bell-crank levers, said stops being normally out of contact with the levers, but operating when the key-bars are pulled to positively engage and move them, substantially as described.

6. In a cash register and indicator, the combination, with a series of targets or tablets, each mounted on independent swinging arms at a point removed from its pivot, of a series of independent key-bars having stops normally

out of engagement with the swinging arms, adapted, when pulled, to positively actuate said arms, and means, substantially as described, for automatically returning an exposed target or tablet to normal position upon the exposure of the next succeeding target or tablet, substantially as described.

7. In a cash register and indicator, the combination, with the series of bell-crank levers bearing the targets or tablets, of the series of operating key-bars normally out of engagement with the levers, arranged, when pulled, to positively move the latter, the swinging retracting-rod arranged between the arms of the bell-crank levers, and connections, substantially as described, between the key-bars and the retracting-rod for causing said rod to return to normal position any disturbed bell-crank lever upon the pulling of any key-bar, substantially as described.

8. In a cash register and indicator, the combination, with the series of bell-crank levers bearing the targets or tablets, of the series of key-bars normally out of engagement with but adapted, when pulled, to positively operate said levers, the retracting-rod arranged between the arms of the bell-crank levers, a vibratory rod adapted to be turned upon pulling any one of the key-bars, and connections, substantially as described, for causing the motion of the vibratory bar to be communicated to the retracting-rod, substantially as described.

9. In a cash register and indicator, the combination, with targets or tablets mounted on swinging arms of different lengths, of guides, substantially as described, for giving lateral support to the tablets and preventing interference with each other when said tablets are swung into and out of view, substantially as described.

10. In a cash register and indicator, the combination of the independent bell-crank levers bearing the targets or tablets, the reciprocating key-bars, the vibratory bar connected so as to be operated upon by each of the key-bars independently, the retracting-rod common to all the bell-crank levers, the sliding plate, pivoted lever, rocking cam, and hinged latch forming the connection between the vibratory bar and the retracting-rod, substantially as described.

11. In a cash register and indicator, the combination, with the series of bell-crank levers bearing the targets or tablets and all mounted upon a common axis, of the retracting-rod carried by arms which are also mounted upon said common axis, and means for operating said retracting-rod, substantially as described.

12. In a cash register and indicator, the combination, with the reciprocating key-bars, of the bearings for the same near its opposite ends and the swinging links to which it is pivoted, substantially as described.

13. The combination, with the reciprocating key-bars, of the vibratory bar T, the rock-shaft U', having an arm, U, operated from the said bar T, the bell, the bell-hammer, and

tripping mechanism, substantially as described.

14. The combination, with the money-drawer, of a movable top or cover therefor preventing the opening of the drawer when pushed in, and devices, such as described, for locking the movable top, substantially as set forth.

15. The combination, with the money-drawer, of a movable top for the same, devices, such as described, for locking the movable top, and means for shifting the top when released from the locking devices, so as to permit the drawer to be opened, substantially as described.

16. In a cash register and indicator, the combination, with a money-drawer, of a movable top for securing the drawer when pushed in, devices for locking the movable top, key-bars, and intervening mechanism between the key-bars and said locking devices, whereby upon the operation of a key-bar the movable top of the drawer will be released and the drawer enabled to be opened, substantially as described.

17. In a cash register and indicator, the combination, with the money-drawer, of a movable top for the same, devices, such as described, for locking the movable top, means for shifting the top when released from the locking devices, and key-bars and intermediate mechanism for operating the locking devices, so as to release the top of the money-drawer each time a key is pulled, substantially as described.

18. In a cash register and indicator, the combination, with the vibratory bar having the series of arms spirally arranged thereon, of a series of reciprocating key-bars provided with lugs or projections for engaging the arms of said vibratory bar, whereby the vibratory bar is moved to a greater or less extent by the operation of a key-bar, accordingly as the lug on said key-bar is nearer to or farther from the corresponding arm of the vibratory bar, substantially as described.

19. In a cash register and indicator, the combination, with a vibratory bar having a series of arms spirally arranged thereon, of the series of reciprocating key-bars provided with lugs for engaging the arms of said vibratory bar, and a registering mechanism actuated by said vibratory bar, substantially as described.

20. In a cash register and indicator, the combination, with a vibratory bar having the spirally-arranged arms, of the series of reciprocating key-bars having lugs or projections, as described, and the spring for returning the bar to normal position after being operated upon by either of the key-bars, substantially as described.

21. The combination, with the ratchet-wheel of the registering mechanism, of the vibratory bar having the spirally-arranged arms and carrying a pawl for engaging with said ratchet, and the series of key-bars having lugs or projections, substantially as described.

22. In a cash register and indicator, the com-

bination, with a series of levers bearing the targets or tablets, the vibratory bar having the spirally-arranged arms, the registering mechanism, and connections between the bar and mechanism to actuate the latter, of the series of reciprocating key-bars having projections for engaging the target-levers and the vibratory bar, substantially as described.

23. In a cash register and indicator, the combination of a series of levers bearing the targets or tablets, the vibratory bar having the spirally-arranged arms, the registering mechanism, the series of reciprocating key-bars, and means, substantially such as described, operated by the key-bars for returning to normal position the displaced tablet-bearing levers, substantially as described.

24. In a cash register and indicator, the combination of a series of bell-crank levers bearing the targets or tablets, the vibratory bar having the spirally-arranged arms, the registering mechanism, the series of reciprocating key-bars, the rod for bringing the bell-crank levers back to normal position, and connecting mechanism, substantially such as described, between such rod and the key-bars, as set forth.

25. In a cash register and indicator, the combination of the series of reciprocating key-bars, the registering mechanism, and the series of targets or tablets actuated by the key-bars, the money-drawer, a locking top for the same, devices for locking said top, and connections, substantially as described, between said locking devices and the key-bars, whereby upon the pulling of a key-bar a target or tablet will be exposed to view, the registering mechanism will be operated, and the top of the money-drawer released, so as to enable the drawer to be opened, as set forth.

26. The combination, with the movable frame carrying the gear-train and indicators and the spring for automatically resetting the registering mechanism, of the pinion-shaft with which the registering mechanism is thrown into and out of connection, substantially as described.

27. A registering mechanism consisting of a train of gears mounted upon a movable frame, in combination with a pinion-shaft with which the first gear of the train engages, and a spring

operating to keep the gear in mesh with the pinion-shaft, substantially as described.

28. A registering mechanism consisting of a gear-train mounted upon a movable frame, in combination with a pinion-shaft with which the first gear of the train engages, the spring operating to keep the gear-train in mesh with said pinion-shaft, and the cam-lever for moving the frame against the tension of the spring to throw the gear out of connection with the pinion-shaft, as described.

29. The combination, with the gear-train of the registering mechanism, of the spring for resetting said mechanism, the lug or stop on the last gear of said train, and the spring-detent with which said stop or lug engages, substantially as described, and for the purpose specified.

30. In a cash-register, the combination, with the series of bell-crank levers pivoted upon a vertical shaft and having horizontal arms of different lengths to which tablets are attached, of a series of keys adapted to co-operate with one of the arms of the levers for causing their rotation on the shaft, substantially as described.

31. In a cash-register, the combination, with a series of bell-crank levers mounted on a vertical shaft and having horizontal arms of different lengths to which tablets are attached, of a series of key-bars adapted to engage each of the levers for actuating them, a vibratory bar common to all the levers, and connections between the key and retracting bars for causing the operation of the latter by the operation of any of the former, substantially as described.

32. In a cash-register, the combination, with the series of bell-crank levers pivoted upon vertical axes, having arms of different lengths on which are mounted vertical arms of different lengths carrying tablets, of a series of keys adapted to co-operate with one of the arms of the levers for causing their rotation on the axes, substantially as described.

WALES ALDRICH.
